United States Patent Office

Des. 194,077
Patented Nov. 13, 1962

194,077

PHOTOGRAPHIC PROJECTOR

Zoltan Takats, Vestal, N.Y., assignor to General Aniline
& Film Corporation, New York, N.Y., a corporation
of Delaware

Filed Aug. 10, 1959, Ser. No. 57,130

Term of patent 14 years

(Cl. D61—1)

FIG. 2

FIG. 1

FIG. 3

FIG. 1 is a perspective view of the front and one side of a photographic projector showing my new design;

FIG. 2 is a perspective view of the rear and one side thereof; and

FIG. 3 is a top plan view thereof.

I claim:

The ornamental design for a photographic projector, substantially as shown and described.
